CAMP COT CANOPY

Howard H. Ham, Kingsville, Tex.

Application March 17, 1947, Serial No. 735,051

8 Claims. (Cl. 135—5.1)

1

This invention relates to certain new and useful improvements in camp cot canopies, and particularly to canopies for camp cots of the folding type, although not necessarily restricted thereto.

The primary object of the invention is to provide a canopy which is readily applicable to and removable from a cot, which when applied and closed will give complete protection against the weather, and which embodies means to allow ventilation when desired while excluding insects and other pests.

A further object of the invention is to provide a canopy which may be securely attached to the cot by means readily attachable to and detachable from the cot, and which canopy comprises a frame and a cover adapted when taken down or removed to be disposed in compact form for storage or transportation.

A still further object of the invention is to provide a canopy having screened openings to allow entrance of air, and light, if desired, and flaps for closing the openings and serving in open position as awnings therefor, together with means for holding the flaps in open and closed positions.

A still further object of the invention is to provide a take-down canopy frame and cover of novel construction whereby the foregoing and other objects and advantages of the invention may be carried into practical effect.

In the accompanying drawings showing a preferred embodiment of the invention,

Fig. 1 is a view in side elevation of the canopy applied to a cot and showing the adjacent side flap secured in open position to form an awning and to admit air or air and light through the associated screen.

Fig. 2 is a top plan view of the cot and the canopy frame applied thereto as it appears when the canopy cover is removed.

Fig. 3 is an end elevation of the parts shown in Fig. 2, looking toward the head of the cot.

Fig. 4 is an end view similar to Fig. 2 with the cover applied and showing the side flaps in open or elevated position and the head end flap partially opened.

Fig. 5 is a detail section on the line 5—5 of Fig. 1.

Fig. 6 is a detail sectional plan view showing the mode of connecting the lower end of the longitudinal frame bow to the end rail at the lower end of the cot.

Fig. 7 is a detail vertical section on the line 7—7 of Fig. 6.

Fig. 8 is a detail section through the lower edge of a side closure flap showing the engagement of

2

the upper end of a holding rod with a keeper strip therein.

Fig. 9 is a sectional view of one of the keeper brackets showing the engagement of the lower end of a holding rod therewith.

Fig. 10 is a view of the canopy cover outspread.

Fig. 11 is a perspective view of one of the brackets.

Referring now more particularly to the drawings, 1 represents a camp cot frame of a well-known folding type, to which the canopy structure is in the present instance shown applied, although it is to be understood that the canopy structure in the form disclosed or in slightly modified form may be adapted for use in connection with other types of cots or conventional bedsteads. This cot frame 1 comprises side rails 2 and 3, a head rail 4, and a foot rail 5, said head and foot rails being provided with end extensions 4' and 5', and head and foot and intermediate pairs of crossed legs 6, 7 and 8, the legs of each pair being pivoted to each other and the sets of legs being pivoted to the side rails, as shown at 6', 7' and 8', in a well known manner, for folding and unfolding actions. The cot frame supports the usual type of cot bottom 9. The cot frame may be made of wood or metal, or a combination of these materials.

In carrying my invention into practice I provide a canopy structure comprising a sectional demountable canopy supporting frame and a cover adapted to be supported thereby and secured to the cot frame.

The canopy supporting frame consists of a longitudinally extending frame member or bow 10 and a pair of transversely extending substantially semi-circular or semi-elliptical frame members or bows 11 and 12. These bows are preferably formed of strips of more or less resilient sheet metal. The bows 11 and 12 are adapted to be disposed above and across the cot at the head and intermediate portions thereof and fitted at their ends in keeper members 13 secured to the side bars 2 and 3 and which may be formed independently of or as component parts of holding brackets 14, as hereinafter described. The ends of the bows 11 and 12 may be slidably fitted down into these keepers in which they are held by the spring tension of the bows, and they may be withdrawn upwardly therefrom whenever it is desired to remove the bows. The bow 10 is adapted to be extended longitudinally of and above the cot in the longitudinal center line of the cot between its head and foot and to rest upon the bows 11 and 12, to which and to the

foot end of the cot it is suitably secured. As shown in the present instance, the bow 10 is secured to the bow 12 by any suitable type of detachable fastener 15, such as a bolt and wing nut, and it may be secured at its head end to the bow 11 by a similar type of fastener 16. This end of the bow 10 may be hooked, as shown in Fig. 5, to engage the bow 11 and add to the security of the connection at this point, but the engaging hook may be omitted if desired. At its lower or foot end the bow 10 is slidably fitted in a keeper 17 secured to the foot rail 5 from which it may be readily withdrawn in removing the canopy frame from the cot. The keeper 17 may be similar in form to the keepers 13 in the event that the latter are formed independent of the brackets 14, and these keepers may be welded or otherwise secured to the cot frame. It will be observed that the bow 11 is of greater length than the bow 12 and extends on an arc of greater radius when applied, and hence is relatively higher than the bow 12, for a purpose more fully hereinafter described. The bows of the canopy supporting frame constructed as described obviously may be readily and conveniently applied to the cot frame for use and as readily and conveniently removed therefrom. When removed the strips forming the bows may be nested together and coiled to form a compact bundle for storage or transportation.

The holding brackets 14 are welded or otherwise secured to the rails 2 and 3 at the head end and intermediate portion of the cot frame. Each bracket comprises a body plate 18 having outwardly projecting upper and lower holding lugs or ears 19 and 20, the said ears having tapered openings 19' and 20', the opening 19' being larger than the opening 20' and arranged out of alignment thereof or farther outward relative to the body plate. A keeper 13 may be formed as an integral part of this bracket, or, as stated, the keepers may be formed independent of the brackets. Each bracket, with or without a keeper, may be made in the form of a casting or stamping, as found most expedient or desirable for use.

The canopy cover 21 comprises an elongated body of a suitable strong, durable and waterproof material and consisting of a central oblong rectangular body portion 22 and side wing portions 23 of a length to extend from the head bow 11 to the end rail 5 and to rest upon the bows and to depend at the sides thereof and form an enclosure above the bottom 9. When this cover is applied the lower end of the body portion 22 laps over the end rail 5, while the upper end of the body portion projects slightly beyond the bow 11. At the lower ends of the wings holding loops 24 are provided for engagement with the rail extensions 5' whereby the cover is secured at that end to the foot of the cot. If desired strings or other like fastening elements 25 may be provided at the upper or head end of the body 22 to secure the cover at that end to the bow rail extensions 4'. Also if desired suitable auxiliary fastening elements may be provided to secure the cover at proper points to the bows and to the rails 2 and 3 if found expedient or necessary. I have not shown such fastening elements, as they may or may not in practice be used, and as they are not essential to a full disclosure of the invention.

The lower or foot portions of the side wings, that is, those portions between the bow 12 and rail 5 are imperforate and designed to remain in closed position when the cover is in use, but the upper or head portion of each wing is designed to be opened and closed to form an inlet and exit

opening and is in the form of a door structure comprising an inner flap 26 and an outer flap 27. The inner flap is in the form of an open rectangular fabric frame secured at its upper edge only to the body 22 and closed by a screen body 28 of mesh wire or mesh plastic material which may be fixedly secured to the frame or removably secured thereto by a zipper type of fastening means. The outer flap 27 is in the form of an imperforate body of fabric secured only at its upper edge to the body 22 for upward and downward movement to open and closed positions.

Outward movement of the flaps 26 and 27 at either side of the cover will permit a person to enter or leave the enclosure or to otherwise have access thereto. When both flaps are let down the opening will be closed in a light-excluding and weatherproof manner. When the flap 26 is let down and the flap 27 opened up, the flap 26 will cover the opening to afford ventilation while excluding insects and other pests.

The flap 27 is provided at its lower edge with a hem 29 in which is fitted a removable strip 29' of metal or other material and which weights the flap to adapt it when closed to maintain its closed position against wind or other pressures. This flap 27 is adapted to be held in a suitably raised position to serve as an awning to shade the doorway and to guard the screened opening from the entrance of light rain or snow in case it is desired to leave the doorway open for entrance of light or for ventilation purposes. To this end the hem 29 and strip 29' are formed with openings 30 for the passage of the upper ends of holding rods 31 having tapered lower ends to engage the openings 19' and 20' in the lugs or ears 19 and 20 of the brackets 14 on the adjacent side rail of the cot frame to support the flap 27 in awning forming position, as shown in Fig 4. When the flap 27 is raised and extended outwardly to a horizontal position the rods 31 which are engaged at their upper ends with the openings 30 will incline or lie at an inward and downward angle so that their tapered lower ends may be engaged with the openings in the lugs 19 and 20. In this operation the tapered form and size of the opening 19' adapts the rods to be fitted down at an angle through the openings 19' and engaged with the openings 20' and to be held in locked position thereby against slipping downward, while at the same time this arrangement of the lugs and openings adapts the rods to be readily removed when it is desired to close the flap. The construction described provides a simple means for holding the flaps 27 in awning forming position whenever desired.

At its head end the cover body 22 is normally open and provided with an inner cover flap 32 and an outer cover flap 33 which may be generally similar in construction to the flaps 26 and used in a similar manner and for similar purposes. The flap 33, however, is adapted to be fully thrown open over and upon the top of the body 22 when it is desired to leave it open for any desired period of time. This flap 33 may also be provided with side wings 33' to be tucked in behind the flaps 26 to provide weather-proof joints at these points whenever required. Other fastening means, such as snap fasteners, may also be used to secure the flaps in closed position to each other and to the rails of the cot frame. The flaps 32 and 33 also allow access to and exit from the interior of the canopy cover and admission or exclusion of light and air. The side and head flaps may be separately or conjointly

opened or closed to suit weather conditions, as will be readily understood. If desired, an eaves flap or strip 34 may be provided at the juncture of the body 22 and upper edge of the flap 33 to serve as a rain shed.

It will be observed that the construction of the canopy frame and cover provides an enclosure which is cross sectionally of substantially semi-circular or semi-elliptical form and desirably deepest at its upper half and gradually slopes longitudinally from its head end to its foot end and also slopes transversely from its longitudinal center toward its side edges which are secured to the side rails of the cot frame. In other words, as the bows 11 and 12 are curved on arcs, the curvature of the bow 11 being on an arc of greater radius than that of the bow 12, and as these bows are curved continuously from their middle portions secured to the bow 10 toward their ends engaging the keepers on the side rails of the cot frame, the covered top will slope longitudinally from its head end to its foot end and its sides will slope from the longitudinal center of the cover toward the side rails of the cot frame. This sloping construction of the canopy cover not only gives a large amount of room space at the head part but greater strength to the set up cover and greater resistance to wind storms, rain storms, and snow or sleet storms when the cot is used for sleeping in the open air, as the sloping surfaces will deflect wind forces and rapidly shed water or sleet and prevent the heavy deposit thereon of snow which cannot be readily brushed off, thus reducing or preventing entrance of wind or moisture or liability of damage to the canopy even in the event of the occurrence of severe storms. The enclosure thus allows the occupant of the cot to secure full protection in inclement weather and ample light and ventilation when desired. The construction provided allows the cover to be turned up at either side to fully air the cot and to conveniently apply and remove bed clothing. As previously stated, the frame parts may be detached when the cover is removed and secured in rolled form for compact storage or transportation. The cover may also be folded or rolled up and packed with the holding rods so that the canopy as a whole may be compactly arranged for storage or transportation.

From the foregoing description, taken in connection with the drawings, the construction and mode of use of my improved cot canopy will be readily understood and its advantages appreciated by those versed in the art without a further and extended description, and it will also be understood that, while the construction disclosed is preferred, changes in the form, proportion and arrangement of parts, falling within the scope of the appended claims, may be made without departing from the spirit or sacrificing any of the advantages of the invention.

Having thus described my invention, I claim:

1. The combination of a cot frame having a keeper on its foot rail and keepers on its side rails located respectively adjacent its head rail and at a point in the region of the longitudinal center of said frame, a canopy frame comprising transverse unitary resilient frame bows having end portions slidably fitted in the keepers on the side rails and held therein by their spring tension and a central, unitary resilient longitudinal frame bow secured to the transverse frame bows respectively at one end and at a point between its ends and having its opposite end slid-

ably fitted and held by spring tension of the bow in the keeper on the foot rail of the cot frame, and a cover disposed on said bows, said cover having side wings coextensive in length therewith and provided with means for securing them at suitable points to the cot frame, each wing being also provided with an opening between its transverse center and head end, an inner screen flap to cover said opening and an outer imperforate flap to cover the screen flap.

2. The combination with a cot frame, of a canopy cover supported on the cot frame having side rails and having an opening, a flap secured at its upper edge to the cover above the opening and adapted to be moved down to cover the opening and upward to uncover the opening and form an awning-like projection, and rods detachably engageable with the free lower edge of the flap and with the side rails of the frame for supporting the flap in its upraised position from said side rails.

3. The combination with a cot frame having side rails, of a canopy cover supported on the cot frame and having an opening, a flap secured at its upper edge to the cover above the opening and adapted to be moved downward to cover the opening and upward to uncover the opening and form an awning-like projection, the lower end of the flap being provided with keeper openings therein, apertured brackets on the side rails of the frame, each having superposed lugs formed with non-aligned openings, and rods engageable at their upper ends with the openings in the flap and having tapered lower ends engageable with the apertured lugs of the brackets to hold the flap in raised position.

4. The combination with a cot frame having side rails, of a canopy cover supported on the cot frame and having an opening, a flap secured at its upper edge to the cover above the opening and adapted to be moved down to cover the opening and upward to uncover the opening and form an awning-like projection, said flap having openings therein adjacent its lower edge, brackets on the side rails of the frame, and rods engaging the openings in the flap and apertures in the brackets and holding the flap in its upraised position.

5. The combination with a cot frame, of a canopy cover supported on the cot frame and having an opening, a flap secured at its upper edge to the cover above the opening and adapted to be moved downward to cover the opening and upward to uncover the opening and form an awning-like projection, the lower end of the flap being provided with keeper openings therein, brackets on the frame each having a pair of superposed lugs provided with non-aligned openings, and rods engageable with the openings in the flap and lugs of the brackets so as to be disposed in an upwardly and outwardly inclined position to hold the flap in raised position.

6. In a canopy construction for camp cots, a canopy cover supporting frame comprising a pair of arched transverse frame bows adapted to be disposed respectively at the head end of a cot frame and at a central point in the length of said frame and to be secured at their ends to the side rails of the cot frame, each of said frame bows when disposed in supporting position extending on the arc of a circle and being continuously curved from the center of its top portion outwardly and downwardly to its ends, and the head end transverse frame bow being curved on an arc of greater radius than the central

transverse frame bow and extending from the cot frame to a level above the level of said central transverse frame bow, a longitudinal frame bow adapted to be secured at one end to the head end transverse frame bow, at an intermediate point in its length to the central transverse frame bow and at its opposite end to the foot rail of the cot frame so as to extend at a sloping angle downwardly between the head end transverse frame bow and foot rail of the cot frame, and means for detachably connecting said bows to each other and to the cot frame rails, each frame bow being formed of a unitary strip of inherently resilient metal, whereby when said frame bows are detached from the cot frame they may be coiled for storage or transportation in a compact nested form.

7. The combination of a cot frame having a keeper on its foot rail and keepers on its side rails located respectively adjacent its head rail and at a point in the region of the transverse center of said frame, a canopy frame comprising arched head end and central transverse frame bows each comprising a strip of inherently resilient metal fitted in the keepers on the side rails and a longitudinal frame bow secured to the transverse frame bows respectively at one end and at a point between its ends and having its opposite end fitted in the keeper on the foot rail of the cot frame, the ends of the frame bows being held under spring tension of the bows in engagement with the keepers, said transverse frame bows when disposed in supporting position each extending on the arc of a circle and being continuously curved from the center of its top portion outwardly and downwardly to its ends, the head end transverse bow being curved on an arc of greater radius than the central transverse frame bow and extending from the cot frame to a level above the level of said central transverse frame bow; and a cover disposed on said bows so as to slope at top from head to foot of the frame and from the center of its top outwardly and downwardly toward opposite sides of the frame and having means for attaching it at suitable points to one of said frames.

8. In a canopy construction for camp cots, a canopy cover supporting frame comprising a pair of arched transverse frame bows adapted to be disposed respectively at the head end of a cot frame and at a central point in the length of said frame and to be secured at their ends to the side rails of the cot frame, each of said frame bows when disposed in supporting position extending on the arc of a circle and being continuously curved from the center of its top portion outwardly and downwardly to its ends, and the head and transverse frame bow being curved on an arc of greater radius than the central transverse frame bow and extending from the cot frame to a level above the level of said central transverse frame bow, a longitudinal frame bow adapted to be secured at one end to the head end transverse frame bow, at an intermediate point in its length to the central transverse frame bow and at its opposite end to the foot rail of the cot frame so as to extend at a sloping angle downwardly between the head end transverse frame bow and foot rail of the cot frame, and means for connecting said bows to each other, each frame bow being formed of a unitary strip of inherently resilient metal and adapted to be slidably engaged at its ends with keepers on the cot frame and to be held under spring tension in engagement therewith.
